UNITED STATES PATENT OFFICE

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY

NAIL DISTRIBUTOR

Original application filed March 14, 1927, Serial No. 175,251. Divided and this application filed February 10, 1930. Serial No. 427,253.

The present invention is concerned with distributing apparatus by which nails or similar fastenings are taken from a source, as a mass held in a receptacle, and delivered in an orderly manner for their utilization in loads of a predetermined number at such a machine as that for attaching heels to shoes and disclosed in the application in my name filed in the United States Patent Office 10 March 14, 1927, with the Serial No. 175,251, and of which this application is a division.

An object of the invention is to improve apparatus of this character, particularly with a view to facilitating the changes for nails of different length or the number used in a nail-ing operation. In this connection, the drum or other nail-container and the raceway or raceways by which the nails are delivered from the container are mounted to move together, as by pivoting their support upon the frame, so that the raceways may be emptied back into the container. Nail-stops are associated with the raceways and are movable between effective and ineffective positions, this being accomplished simultaneously for a plurality of the stops. I have shown means for thus selecting the stops in groups, so the operator may readily determine, with the aid of associated index means, the number of nails to be delivered through the raceways. Nail-reversing abutments or members associated with a raceway or raceways are made movable by connection with a setting member provided with index means, so the desired position of the abutments may readily be determined for any length of nail. Such reversing means, without reference to the manner of its adjustment, is caused to move, during its variation in position to correspond to different nail-lengths, in a direction inclined to the vertical. Consequently, the distances of an abutment from the nail-supporting surface of the raceway and from the wall which limits the movement of the nail during its reversal are simultaneously altered.

In the accompanying drawings,

Fig. 1 is a front elevation of one embodiment of my invention, with parts broken away and in section;

Fig. 2 illustrates in broken side elevation

the setting devices for the nail-stops and reversing abutments;

Fig. 3 shows the nail-separators and stops in perspective;

Fig. 4 is a front elevation of the apparatus, 55 including portions of an associated heel-attaching machine; and

Fig. 5 is a section through the distributing apparatus on the line V—V of Fig. 1.

A column 12 has, at the upper rear portion, 60 a bracket 120, upon which is pivoted about a sleeve 122 a support 124 for the chief elements of the distributor. A pin 126 serves to detachably lock the support upon the bracket in its normal position, and may be 65 removed to allow the support and containing elements of the distributor to be tilted rearwardly for the purpose of emptying the nails. A nail-receptacle or container is carried by the support, this being shown, in part, 70 as a conical casing 128 integral with said support, with its interior accessible through a door 129. Secured to a wall 130 within the casing is a horizontal spindle 132, about which rotates a nail-drum 134, held releasably in place by a hand-nut 136 threaded upon the spindle. Buckets 138 about the drum successively lift the contained nails and empty them upon the diverging receiving walls 140 of the raceways. These raceways, 80 of which eleven are herein shown, may consist of pairs of spaced bars 142, 142, upon which the nails descend, hanging by their heads. To free the raceways of displaced nails which might interfere with the proper delivery, pairs of clearing wheels 144, 144 are arranged upon a shaft 146 at opposite sides of each nail-conveying slot. The wheels are provided with inclined peripheries formed with serrations, and when these 85 are rotated in an anti-clockwise direction (Fig. 5), they act to rake back the displaced nails, either into position between the bars, or so they fall into the casing and return to the drum. To rotate the shaft 146, which is journaled horizontally across the forward end of the casing, it is belted at 150 (Fig. 4) to the driven member of a clutch 152. This member, together with the driving member 90 of the clutch, is rotatable about the sleeve 100

122. Said driving member is belted at 156 to the hub of a main driving pulley (not illustrated), and is controllable to produce engagement or release of the clutch, through 5 a rod 153 extending through the sleeve and provided with a handle 154. From the clearing-wheel shaft, rotation may be communicated to the drum 134 through a train of gearing 158 (Fig. 5), a shaft 160 journaled 10 upon the support, and gearing 162. To empty the distributor of its contained nails, it is tilted upon its pivot, so that the support leaves its seat upon the bracket, and the raceways become sufficiently inclined to cause all 15 the nails in them to flow back by gravity through the open ends of said raceways into the drum. In this position, the distributor is held by contact of depending arms 167 with portions 163 of the frame. All the nails 20 being discharged from the raceways, the operator has only to remove the nut 136, and, lowering the drum from the spindle, empty it. Then it may be filled with nails of another length, restored to its place upon the 25 spindle, and the distributor and its support tipped back to the normal position. Extending between the column and each arm 167 upon the support, is a spring 165, which is under constant tension. This acts as a counterbalance for the weight of the tilting portions of the distributor, both during the nail-emptying operation and during return movement. The double action is due to the fact that the arms 167 pass to opposite sides of 30 the vertical through the pivot 122 during the oscillation of the distributor.

It may be desired to supply nails, as to the jack of a heeling machine, from all the raceways or from but a portion. I have shown 45 five of the raceways as invariably conveying nails, while with the other six raceways means is associated for checking at will the flow through them, the control being exercised in groups. In the present instance, the groups 45 include, respectively, five, seven, nine and eleven raceways, though any other desired combinations might be employed. Mounted upon the support, above each raceway to be governed, upon a spring 164 is a stop-finger 50 166, the point of which may either occupy an effective position, in which it lies in the path of the nails, or may be so raised that it is ineffective. To allow the chosen combination of stop-fingers to be selected to cut off the supply 55 of nails through the corresponding raceways, there extends beneath the fingers a shaft 168 journaled at opposite sides of the raceways. Secured upon the shaft and co-operating with each finger is a cam 170, the finger being forced against the cam by its mounting-spring. Fixed upon one end of the shaft is a handle 172, by which it may be turned, this handle carrying a spring-actuated latch 174, adapted to engage any one of six numbered 60 176 in an index-plate 178. The an-

gular arrangement of the cams about the shaft 168 is such that they come into action in groups corresponding to the numbered positions of the handle. That is, if the operator desires to supply nails through five of the raceways, he will position the handle as appears in Fig. 3 of the drawings, with its latch in the opening numbered 5. All the cams will now permit the stop-fingers to bar the associated raceways, so only those not controlled will be free. Or, when the latch engages the opening numbered 11, the cams act to raise all the fingers, so that the entire series of raceways deliver the nails. 75

Just before the nails leave the body-portions of the raceways and pass upon more steeply inclined ends 179, which insure the proper advance of single nails, they are acted upon by separating devices, which pick them off one by one for delivery. Each device is 80 in the form of a disk 180, having in its periphery a notch 182 of such dimensions that, when brought into registration with the upper or main portion of the raceway, it will receive a single nail, and then, upon rotation of the disk, will transfer this to the lower section 85 179 and release it for delivery. Each disk is secured upon a shaft 184 journaled at one side of the raceway controlled and having fixed upon its lower end a pinion 186. With the entire series of pinions meshes a rack-bar 188 mounted to reciprocate in guides beneath the raceways. The bar is joined, through a pin-and-slot connection 190 (Fig. 5), to a bell-crank lever 192 pivoted upon the support 124. A link 194 is articulated to the bell-crank lever and to a lever 196 fulcrumed at one side of the column. Acting upon the lever is a cam 290 movable by a member 284, which, at definite times in the operation of 95 automatic loading or transferring mechanism for the jack of the associated heel-attaching machine, may be driven by connection to a tubular shaft 260. In this manner, the lever 196, and therefore the separator-disks, are 100 operated in correct time-relation with the loading mechanism. 110

When the nails are to be driven upwardly into the work, as from a jack, they must be delivered with their heads down. To reverse them from the positions they occupy upon the raceways, they contact with abutments 200 (Fig. 2), so located between the ends 179 of the raceway-bars that they restrain the depending points, while the heads, continuing their advance, overbalance on the upper edges of the abutments. The nails therefore enter vertical passages 202 with their points up. These passages are formed between the forward extremity of a bracket 204 secured to the support 124 and a removable wall 206 held in place by screws 208. In case of clogging, this wall may be taken off to clear the passages. To most effectively produce the reversing action, the abutments 125 130

- must be differently located for different lengths of nails. I have therefore mounted them for adjustment in two directions—vertically toward and from the nail-supporting surfaces of the raceways, and horizontally to approach and retreat from the wall 206. The first movement causes the nails to contact with the abutments at points along their lengths at which they best overbalance. 5 The second gives the correct space between the abutment and the wall for the nails to turn without interference. I prefer to obtain the two adjustments simultaneously by a diagonal movement of the abutments, or 10 at an angle to the vertical. For this purpose, each abutment is provided with a slot 210 inclined upwardly and forwardly and having passing through it a supporting rod 212 mounted at its ends in the bracket 204. To 15 move each abutment over the rod 212, there is shown connected to it an eccentric-rod 214 acted on by an eccentric 216 fixed to a shaft 218 journaled in the bracket below the raceways. Secured to one extremity of the shaft 20 25 is a handle 220 having a spring-actuated latch 222 arranged to enter any one of a series of openings 224 in an index-plate 226. The openings 224 may bear designations corresponding to lengths of nails which the distributor is to deliver. As illustrated in Fig. 2, the abutments are adjusted for acting upon the shortest nail which is to be used, the eccentrics 216 holding the abutments at their highest points and nearest to the wall 206. At this 30 time, the lower end of the slot 210 is in proximity to the rod 212. When the shaft 218 is turned by the handle to set the eccentrics at another angle indicated by the index-openings 224, the abutments are moved down upon the rod and simultaneously away from the wall. The upper edges of the abutments therefore engage the longer nails farther from the heads, and greater space is given 35 between these edges and the wall 206 for the nails to reverse. From the passages 202, the nails pass through curved tubes 228 to a set of delivery-tubes 230 mounted in a removable frame 232. The lower ends of the tubes 230 terminate in a foot-plate 234, in 40 which they are arranged according to a nailing design similar to all or a part of the passages in the jack-top. The substitution of the frames 232 with differently arranged tubes will provide for the delivery of the 45 nails in accordance with the design desired for the insertion of the fastenings.
- Having described my invention, what I claim as new and desire to secure by Letters Patent of the United States is:
- 60 1. In a nail-distributor, a frame, a nail-container movable upon the frame to empty the nails therefrom, a raceway mounted upon the container and arranged in the movement of said container to deliver rearwardly to the container nails which it carries, and means

arranged to counterbalance the weight of the container and raceway during their movement.

2. In a nail-distributor, a frame, a nail-container movable upon the frame to empty the 70 nails therefrom, a raceway mounted upon the container and arranged in the movement of said container to deliver rearwardly to the container nails which it carries, and means arranged to counterbalance the weight of the container and raceway during their movement both to the delivering position and in their return to normal.

3. In a nail-distributor, a frame, a support pivoted upon the frame, a nail-drum rotatable upon the support, and a slotted raceway carried by the support and receiving nails from the drum and conveying them hanging by their heads through the slots, the support being movable upon its pivot to empty the 80 raceway rearwardly, said raceway being open at its upper extremity to permit the passage of the nails through the opening into the drum.

4. In a nail-distributor, a frame, a support pivoted upon the frame, a nail-drum rotatable upon the support, raceways carried by the support and receiving nails from the drum, the support being movable upon its pivot to empty the raceways into the drum, 90 and a tension-spring extending between the support and frame.

5. In a nail-distributor, a frame, a support pivoted upon the frame, a nail-drum rotatable upon the support, raceways carried by 100 the support and receiving nails from the drum, the support being movable upon its pivot to empty the raceways into the drum, and a tension-spring extending between the support and frame, said spring being arranged to exert a force resisting movement of the support both to the raceway-emptying and normal positions.

6. In a nail-distributor, raceways, a nail-stop for each of a plurality of the raceways, 110 said stops being movable between effective and ineffective positions, and means arranged to position simultaneously a plurality of the stops in variable groups, the magnitude of the groups being determined by the positioning means.

7. In a nail-distributor, raceways, a nail-stop for each of a plurality of the raceways, 120 said stops being movable between effective and ineffective positions, a member for positioning each stop, and means common to all the position-determining members and arranged to set them in different groups respectively comprising different stops in their effective positions.

8. In a nail-distributor, raceways, a movable nail-stop for each of a plurality of the raceways, a rotatable shaft extending adjacent to the stops, and groups of cams secured 130

to the shaft, said groups of cams respectively acting upon different groups of stops.

9. In a nail-distributor, raceways, a movable nail-stop for each of a plurality of the raceways, a shaft, cams upon the shaft acting upon the stops, and means arranged to move the cams and render effective different groups of said cams.

10. In a nail-distributor, raceways, a movable nail-stop for each of a plurality of the raceways, a shaft, cams set at different angles about the shaft and acting upon the stops, a handle fixed to the shaft, and an index member with which the handle co-operates.

11. The combination with an inclined nail-conveying raceway comprising spaced bars between which nails may travel supported by their heads, of a reversing member arranged between the bars to contact with the descending nails and extending below said bars, a wall situated at the end of the raceway opposite the depending portion of the reversing member and furnishing therewith a discharge-passage for the reversed nails, and means arranged to move the reversing member toward and from the wall.

12. The combination with an inclined nail-conveying raceway comprising spaced bars between which nails may travel supported by their heads, of a reversing member arranged between the bars to contact with the descending nails and extending below said bars, a wall situated at the end of the raceway opposite the depending portion of the reversing member and furnishing therewith a discharge-passage for the reversed nails, and means arranged to move the reversing member simultaneously toward and from the supporting surface of the raceway and toward and from the wall.

13. The combination with an inclined nail-conveying raceway, of a nail-reversing member acting upon nails descending the raceway and being movable for action upon different lengths of nails, a movable setting member provided with index means, and connections between the setting member and reversing member arranged to shift said reversing member upon movement of the setting member and in accordance with the indication given by the index means.

14. The combination with an inclined nail-conveying raceway, of a nail-reversing abutment movable in the raceway, and connections between the abutment and raceway comprising a co-operating projection and slot, said slot being inclined to the vertical.

15. The combination with an inclined nail-conveying raceway, of a nail-reversing abutment movable in the raceway, a rotatable member, and actuating connections between the member and abutment.

16. The combination with an inclined nail-conveying raceway, of a nail-reversing abutment movable in the raceway, connections

between the abutment and raceway comprising a co-operating projection and slot, said slot being inclined to the vertical, a rotatable shaft, an eccentric fixed to the shaft, an eccentric-rod connected to the abutment, a handle fixed to the shaft, and an index member with which the handle co-operates.

17. The combination with a series of nail-conveying raceways, of a nail-reversing abutment movable in each raceway, a shaft extending adjacent to the raceways, an eccentric fixed upon the shaft for each abutment, an eccentric-rod connecting each eccentric to its abutment, and index means associated with the shaft.

18. The combination with a series of nail-conveying raceways, of a nail-reversing abutment movable in each raceway and having a slot inclined to the vertical, a projection from the corresponding raceway entering the slot, a shaft extending adjacent to the raceways, an eccentric fixed upon the shaft for each abutment, an eccentric-rod connecting each eccentric to its abutment, and index means associated with the shaft.

In testimony whereof I have signed my name to this specification.

JOHN F. STANDISH.
